UNITED STATES PATENT OFFICE.

HARRY E. CAMPBELL, OF NEW YORK, N. Y., ASSIGNOR TO CAMPBELL METAL WINDOW CORPORATION, OF BALTIMORE, MARYLAND, A CORPORATION OF MARYLAND.

WINDOW-SASH BOOSTER.

Application filed April 13, 1922. Serial No. 552,321.

To all whom it may concern:

Be it known that I, HARRY E. CAMPBELL, a citizen of the United States, residing at New York, in the county of New York and 5 State of New York, have invented a certain new and useful Improvement in Window-Sash Boosters, of which the following is a specification.

The invention is a booster for initially and 10 directly applying the force exerted by the operator to move a sliding window sash away from its seat, against which it may be tightly held. This is done through the agency, preferably, and as here shown, of 15 the handle attached to a rail of said sash, whereby the opening of the sash is ordinarily effected. The handle is pivoted to the rail so that when first grasped by the operator it is swung in the direction of opening 20 movement of the sash. This curvilinear movement of the handle is then translated by suitable mechanism into longitudinal rectilinear movement of a pusher rod which abuts on the window frame, and so initially 25 and directly applies the whole power exerted by the operator to force the sash away from its seat, after which the operator uses the handle in the ordinary way to complete 30 the opening of the sash to whatever extent is desired.

In the accompanying drawing—

My booster is shown applied to the type of metal window set forth in U. S. Letters Patent Nos. 1,222,357 and 1,222,358, granted 35 to me April 10, 1917, and Patent No. 1,237,295, granted to me Aug. 21, 1917. Fig. 1 is a vertical section through the sill and the lower portion of the lower sliding sash, showing the position of the parts when the 40 sash is seated on the sill. Fig. 2 is a horizontal section on the line 2, 2 of Fig. 1. Fig. 3 is a vertical section on the line 3, 3 of Fig. 2, showing the position of the parts when the sash is raised from its seat on the 45 sill.

Similar numbers and letters of reference indicate like parts.

My aforesaid patents disclose the type of metal window to which my booster is here 50 shown applied and, therefore, the details of said window are herein omitted. Generally the frame comprises a sill 4 and jambs 5, the said jambs having in their inner walls vertical gaps 6, 7 in which travel 55 lateral plates (not shown) which extend

from the side rails of the upper and lower sashes. My booster is here shown attached to the rear side of the bottom rail of the lower sash 8. Said bottom rail is formed of two sheet metal plates 9, 10 secured in 60 contact. The plate 9 is shouldered at its upper portion so as to form with plate 10 a channel for the reception of the glass pane 11. Plate 10 is shouldered at its lower portion so as to form with plate 9 a channel 65 12 for the reception of a rib 13 on the sill 4, which rib extends transversely across said sill. The sides of rib 13 are preferably inclined more than are the sides of the channel 12, so that when the sash is closed the rib 70 13 will become wedged in said channel, thus closing the joint and preventing access of drafts of external air through said joint and into the building or room in which the window may be installed. 75

The construction of my booster now to be explained is such that despite any tightness of the joints between sash and frame, and especially between bottom sash rail and sill rib, as above described, the sash can 80 nevertheless easily be moved from its seat by the operator.

A is a metal lug secured by screw bolts 14 to a flange of plate 10 and by screw bolts 15 to the rear side of the bottom sash rail, said screws 15 also here serving to attach 85 together the rail plates 9 and 10. Said lug has two forwardly turned arms B. The parallel recesses C or loops below said arms are inclined downwardly and their open front 90 ends are closed by the sash plate 10, against which the lug bears. The rear ends 16 of said recesses are arc-shaped and receive the shaft D, Fig. 1, longitudinal displacement 95 of which is prevented by collars E, Fig. 2, thereon. Fast on, or integral with, shaft 100 D is a lever arm F which lies between the lug arms B. To the end of arm F is pivoted one end of the pusher rod G. Said rod extends through the lug A, and, as shown in Fig. 1, normally abuts on the upper flat surface of sill rib 13. A bail-shaped handle H is secured to the ends of shaft D. It will be obvious that the handle H and 105 arm F unitedly form a swinging lever, of which shaft D is the pivot.

When the sash is seated, as shown in Fig. 1, the shaft D lies in the arc-shaped ends 110 16 of the recesses C. In order to operate the device, the operator simply grasps the

handle H and moves the sash by it, exactly as he would do if the handle were rigidly attached to the sash in the ordinary way. As he grasps said handle, he first swings it on its pivot shaft D, and the arm F on said shaft then forces down the pusher rod G upon the sill rib 13. The whole force exerted is then brought into a straight line in the direction of desired motion of the sash 10 and with a leverage represented by the difference in lengths of the lever arm formed by the handle H and that of the lever arm F measured from the center of pivot shaft D. By reason of the inclination of the recesses C, when the handle is moved upwardly, the shaft D is free to move down said incline for a short distance, as shown in Fig. 3, and thus adjusts its own position with reference to the rectilinear movement 15 20 of the pusher rod G, so that any binding of the linked parts in the lug is prevented.

While I have herein shown my booster applied to a special type of metal window, to which it is especially well adapted, it is 25 to be understood that the invention is not limited to that or any other specific type, but, on the contrary, may be applied to any window in which there is a sliding sash and fixed seat therefor. It will also be obvious 30 that my device may be applied to a horizontally sliding as well as to a vertically sliding sash.

I claim:—

1. A window-frame, a sliding sash therein, a lever handle mounted on said sash adapted to be used in the ordinary manner to open or close such sash throughout the full movement thereof, and a member pivoted to said lever handle and normally abutting on said frame; the said parts being so arranged that, the sash being closed, a movement of the handle resulting from the

ordinary movement to open the sash will cause said pivoted member to force said sash away from its seat. 45

2. A window-frame, a sliding sash therein, a lever having a handle portion and an arm shorter than the handle portion, such lever being pivoted to the sash in such a way that an upward movement of the handle portion will cause a downward movement of such shorter arm and a member adapted to be moved by such shorter arm to exert pressure against the frame when the handle is raised, so that when the handle 50 55 is used to open the window in a normal manner, the sash will be forced away from its seat.

3. A window-frame, a sliding sash therein, a lug on the rear side of said sash having shaft bearings, a shaft in said bearings, lever arms on said shaft, and a longitudinally movable member pivoted to one of said arms and extending through said lug and normally abutting on said frame. 60 65

4. A window-frame, a sliding sash therein, a lug on the rear side of said sash having outwardly inclined recesses, a shaft in said recesses, two lever arms of different lengths carried by said shaft, a longitudinally movable pusher rod pivoted to the shorter of said arms and extending through said lug and normally abutting on said frame. 70

5. The combination of claim 3, further including as the other of said lever arms a bail-shaped handle connected to opposite ends of said shaft.

In testimony whereof I have affixed my signature in presence of two witnesses,

HARRY E. CAMPBELL.

Witnesses:

GERTRUDE T. PORTER,
